UNITED STATES PATENT OFFICE

MARTIN VAN BUREN DAVIS, OF HARRISON, ARKANSAS.

DEVICE FOR RAISING AND LOWERING WEIGHTS.

SPECIFICATION forming part of Letters Patent No. 378,293, dated February 21, 1888.

Application filed November 3, 1887. Serial No. 254,197. (No model.)

To all whom it may concern:

Be it known that I, MARTIN VAN BUREN DAVIS, a citizen of the United States, residing at Harrison, in the county of Boone and State 5 of Arkansas, have invented a new and useful Improvement in Devices for Raising and Lowering Weights, of which the following is a specification.

My invention relates to an improvement in 10 devices for raising and lowering weights; and it consists in the peculiar construction and combination of devices, that will be more fully set forth hereinafter, and particularly pointed out in the claims.

15 In the accompanying drawings, Figure 1 is a perspective view of a hoisting device embodying my improvements, showing the same in operation. Fig. 2 is a cross-sectional view of the same.

20 A represents a vertical rectangular supporting-frame, which is mounted on a base-frame, B, and is provided at its upper side with a cross-bar, C.

D represents a yoke, which is arranged transversely on the cross-bar, and from the ends of the said yoke depend ropes E. The lower ends of these ropes are attached to a winch, F, near the ends thereof, and are adapted to be coiled or uncoiled on the said winch when 30 the latter is rotated. The winch is provided with a suitable crank, G.

H represents a pair of hangers, which are provided with depending diverging arms I, having eyes K at their lower ends. Each of these hangers is provided at its upper end with an integral collar, L, by means of which they are swiveled to the winch near the ends thereof, as shown.

M represents a pair of slings, each one of 40 which comprises a cross-bar, N, having cords or ropes O at its ends adapted to be connected to the eyes of the hanger-arms.

P represents a hook, which is adapted to engage the crank, and is connected to one of the 45 ropes O.

The operation of my invention is as follows: In order to raise the weight or heavy object, such as shown at a, the cross-bars of the slings are first placed under the same and connected

to the hanger-arms, and the operator then 50 grasps the crank and turns it in the direction indicated by the arrow in Fig. 1, thereby causing the ropes E to be coiled or wound on the winch, and consequently causing the latter to rise with the weight. When the weight has 55 been elevated to the required height, it may be suspended by engaging the hook P with the crank, which will effectually prevent the winch from rotating in a retrograde direction and lowering the weight.

60 A hoisting apparatus thus constructed will be found particularly useful in taking the beds from wagons and in lowering the same thereon; but it may be used for elevating heavy objects of various kinds, as I do not limit myself in 65 this particular.

When the device is to be used for raising bales of cotton and hay and similar objects, a platform will be secured on the cross-bars of the slings.

70 Having thus described my invention, I claim—

1. In a hoisting apparatus, the combination of the depending ropes E, the winch secured to the lower ends of said ropes and provided 75 with an operating-crank, the hangers swiveled to the winch, and the slings attached to the hangers, substantially as set forth.

2. The combination, in a hoisting apparatus, of the depending ropes E, the winch secured to the lower ends of the said ropes, adapted to coil and uncoil the same and provided with the crank, the hangers swiveled to the winch and having the diverging arms, the slings M, attached to the lower ends of the 85 said hanger-arms and adapted to support the object to be hoisted, and the hook adapted to engage the crank-arm and thereby prevent the winch from rotating, for the purpose set forth, substantially as described.

90 In testimony that I claim the foregoing as my own I have hereto affixed my signature in presence of two witnesses.

MARTIN VAN BUREN DAVIS.
